PAPER FEEDING MACHINE

Frank L. Cross, Port Washington, N. Y., assignor
to Cross Paper Feeder Company, Boston, Mass.,
a corporation of Massachusetts

Application June 3, 1933, Serial No. 674,177
Renewed November 22, 1934

6 Claims. (Cl. 271—38)

Paper feeding machines employing sheet separating combing wheels usually comb the top sheets of a pile or bank toward the end of a table from which the sheets are delivered, the combing 5 wheels being arranged close to the delivery edge of the table so that upon the completion of a combing separating operation the combing wheels are raised from the pile or bank and supported in raised position until the top sheet has been 10 completely fed from the pile. In this feeding-off operation the major part of the sheet must pass beneath the combing wheels before they can be returned to the pile or bank for their succeeding 15 operation. This required holding of the combing wheels out of operation for such a material part of the feeding time causes the slowing up of the feeding operation to such an extent that a feeding speed equal to the normal rapid operation of the modern printing press cannot be obtained. 20

The main object of the present invention is to improve the construction of combing paper feeding machines to enable them to maintain a more rapid operation to meet modern requirements 25 and to this end the present invention comprises a reorganization of the feeding machine whereby the sheets are taken from a pile or bank rearwardly or reversely of their separating movement under the action of the sheet combing devices. 30 This object is further advanced by providing sheet delivery mechanism over the rear edge of a preliminarily separated bank of sheets with means for lifting the rear edge of a sheet away from the pile or bank and shifting it rearwardly 35 into the bight of delivery drop rollers which complete the removal of the sheet from the pile or bank. The combing wheels act upon a fanned out top portion of a pile or bank of sheets for further shifting and separating the sheets in the same direction they are fanned out and toward 40 suitable tripping devices which arrest the preliminarily separated sheets and cause the combers to be raised from the pile or bank. The delivery devices next take the rear edge of the separated top sheet, raise it from the pile or bank, while air is blown beneath the raised rear edge, and pass it rearwardly from the pile, it being clear 45 that, since the combing wheels are arranged adjacent to the leading edge of the bank of sheets in the separating operation, a very small part of the top sheet has to be drawn beneath the combing wheels to again expose the fanned out pile or bank for the subsequent action of the combing wheels which are consequently timed to drop back 50 into operation immediately after the separated

top sheet has passed from beneath them. With this rearrangement of the feeding machine a much more rapid feed of sheets to the press can be maintained.

The improvements of the present invention are particularly applicable to a double table continuous feeding machine of well-known type excepting in the rearrangement of such machine to use the lower table for the bank supply table and the upper table for the feed table, the fanned out bank of sheets being passed from the lower supply table up through the bank reversing throat to the feed table where the final separating combing devices act to move the sheets toward the controlling tripping devices and the delivery mechanism operates above the tail of the sheets for feeding the sheets off in the reverse direction. In the application of the invention to the continuous form of feeder the bank of sheets is supplied from time to time upon the lower supply table more conveniently and with less lifting effort than with the old form of continuous feeder which requires the operator to carry the bundles of paper up a much greater distance to the upper table. 25

In order that the invention may be fully understood it will first be described with reference to the accompanying drawings and afterwards more particularly pointed out in the annexed claims. 30

In said drawings

Figure 1 is a side elevation of the improved paper feeding machine as it is applied to a printing press;

Figure 2 is a detail side elevation of part of the same taken from the opposite side of the machine to better illustrate the driving connections; 35

Figure 3 is a side elevation of the machine similar to Figure 1 on a larger scale;

Figure 4 is a detail vertical longitudinal sectional view of the machine on a still larger scale, 40 the parts being in the position they assume when operating upon a full bank of fanned out sheets;

Figure 5 is a detail view of part of the sheet feed-off delivery mechanism of the machine showing the parts in position to take a sheet from a thin or partially depleted bank of fanned out sheets; 45

Figure 6 is a similar detail view of part of the same mechanism in shifted position in the operation of delivering a sheet; 50

Figure 7 is a vertical transverse sectional view taken on the line 7—7 of Figure 4;

Figure 8 is an enlarged side elevation of the upper right hand portion of the machine shown in Figure 3; and 55

Figure 9 is a plan view of the same.

The improved sheet separating feeding machine has been shown in the accompanying drawings applied to a continuous form of feeding machine embodying supply and feed tables connected by a pile reverse throat. In the rearrangement of this type of feeding machine best suited for the application of the present improvements the lower table is employed as the supply or bank receiving table while the upper table is used as a final separating and feeding table. With this rearrangement it will be clear that the work of piling bundles of paper sheets upon the receiving table is accomplished with less effort than with the old form of continuous feeder. In the new arrangement the operator is required to lift the bundles of sheets to the receiving end of the lower table where he conveniently arranges the new supply of sheets in partially fanned out condition with reference to the fanned out bank already in place in the machine. In the old form of continuous feeder the operator was compelled to climb a number of steps to place the new supply of sheets upon the receiving end of the top table.

In the drawings 1 is the lower bank supply table having journalled in suitable brackets 2 and 3 mounted upon its opposite ends the pulley shafts 4 and 5 upon which are carried the belt supporting pulleys 6 and 7 over which operate the endless conveying belts 8 whose upper runs pass from the receiving end to the delivery end over the upper surface of the table 1.

The receiving end of the table 1 is supported by brackets 9 secured to the under surface of the table and pivotally mounted at 10 upon links 11 projecting up from a shaft 12 upon which are journalled the grooved wheels 13 which operate upon track bars 14 mounted upon upright frame pieces, one of which is shown at 15.

Side bars 16 extend from shaft 12 to the lower ends of angle frame members 17 which carry the transverse shaft 18 supporting at its ends the grooved wheels 19 which operate upon the track bar 20 secured to the upright frame members 21. One of the side bars 16 carries a depending arm 22 which is threaded upon an adjusting screw 23 journalled at its ends in a frame member 15 and a stationary upright 24. The screw 23 has a hand wheel 25 by which it can be rotated to cause the feeder frame to be moved toward and away from the printing press, the wheeled feeder frame operating upon the track bars 14 and 20.

26 is the pile reversing drum or cylinder mounted upon shaft 27 which is freely journalled at its ends in the angular frame side bars 17.

The inner end of the supply table 1 is supported upon links 28 pivoted at their opposite ends upon shafts 5 and 18 above referred to. Endless hugging belts 29 pass around suitable belt pulleys mounted upon shafts 5 and 18 and also pulleys 30 mounted upon shaft 31 carried in the upper ends of the curved arms or levers 32 pivotally supported at their lower ends upon the shaft 18. Tension rollers 33 journalled upon studs carried by arms 34 pivoted upon the shaft 18 and engaged by tension springs 35 are caused to yieldingly engage the hugging belts 29 between shafts 18 and 31 to hold them in close contact with the fanned out bank or pile as it passes from the lower table 1 around the reversing drum 26 to the upper feed table 36 which will now be described.

36 is the upper feed table fastened to upper side bars 37 which are in turn fastened to the

upper part of the side bracket 11 at one end and supported near its outer end by upright brackets 38 extending from the side bars 16 to the upper table 36. This upper table 36 carries a pulley shaft 39 upon which belt pulleys are mounted, the table being slotted to permit the belt pulleys to operate with their peripheries above and below the table. Endless feed belts 40 extend around the drum 26 over the upper surface of the main portion of the table 36 around the pulleys upon shaft 39 through the table slots (not shown) and over guide pulleys 41 carried in brackets 42 projecting beneath feed table 36.

The transverse shaft 39 carrying belt pulleys upon the feed table 36 is provided at one end with a ratchet wheel 43 operated by a dog 44 mounted upon a rocking lever 45 pivoted on shaft 39 and connected through link 46 with a rock arm 47 upon rock shaft 47a which also carries the curved rock arm 47b acted upon by cam 47c upon the shaft 12. A controlling mechanism is connected to the ratchet operating mechanism in any of the well-known ways for determining the amount of feeding action to be applied to the bank carrying belts 8, 29 and 40. In the mechanism illustrated in the drawings in the present case but not described in detail, this control of the bank feed is actuated by the time periods of operation of the comber mechanism in the manner employed in the well-known Cross paper feeding machine now in commercial use. The theory of the operation is to feed the bank more or less as the combing mechanism is required to operate greater or less time in combing the sheets into final registered position for removal from the feed table.

The pulley shaft 39 which is intermittently operated through the comber control mechanism is provided upon its end opposite the ratchet wheel 43 with a sprocket wheel 48 over which operates a driving sprocket chain 49 operating around a similar sprocket wheel 50 keyed to the drum shaft 27 through which the bank advancing belts 40 and drum 26 are driven. A bevel gear 51 also keyed to the drum shaft 27 meshes with and drives a bevel gear 52 keyed to the upper end of an inclined shaft 53 journalled in bracket bearings 54 integral with or secured to the outer face of one of the frame arms 17. Shaft 53 carries at its lower end a bevel gear 55 meshing with and driving bevel gear 56 secured to the end of shaft 18. This shaft 18 carries a sprocket wheel 57 driving a sprocket chain 58 which operates upon and drives a sprocket wheel 59 keyed to the shaft 5 by which the bank advancing belts 8 are operating over the supply table 1. The shaft 18 also drives a sprocket chain 60 which operates over a sprocket wheel 61 upon the shaft 31 to drive the bank hugging belts 29.

The fanned out bank of sheets indicated at S passes from the feed supply 1 through the bank reversing throat formed by the drum 26 and the hugging belts 29 and from this throat the bank passes above drum 26 on belts 40 to the top or feed table 36 in conjunction with which operate the final separating combing devices and the feed-off delivery devices.

Just after the bank of sheets S passes over the drum 26 it is engaged by a retaining weight preferably in the form of a heavy roller 62 which is freely journalled in the forward ends of the curved arms 63 pivotally mounted upon a transverse shaft 64 carried in the auxiliary frame side plates 65 rigidly attached to the machine frame 75

66 of the printing press with which the automatic feeder cooperates.

At or adjacent to the end of feed table 36 furthest away from the drum 26 are auxiliary side frames 67 supporting the sheet combing separating mechanism which imparts a final separating action to the fanned out bank of sheets. This mechanism may be of any approved form, but is preferably of the general construction of the separating combing mechanism now employed in the commercial Cross feeding machines, or, as is shown in Cross Patent No. 812,260 dated February 13, 1906. Of this mechanism 68 represents one of a pair of continuously rotating combing wheels 15 under the control of automatic mechanism for periodically moving them into engagement with the bank of sheets, and 69 represents one of a pair of sheet stops or tripping fingers actuated by the advance edge of a sheet to automatically arrest the action of the combing wheels by causing them to be raised away from the bank of sheets.

Each of the combing wheels 68 is journalled upon the end of an arm 110 loosely mounted on a continuously running shaft 111, to which the combing wheel is geared through a series of intermeshing gears (not shown) by which it is caused to rotate continuously. The comber supporting arm 110 is connected by a link 112 with a shaft 113, said link being loose upon said shaft. The shaft 113 is carried in arms 114 secured to a rocking sleeve 115 loosely mounted upon a transverse rod 116 supported in the side frames 67. The raising and lowering of the shaft 113 throws the combing wheel out of and into action.

The mechanism for raising the combing wheel and thus throwing it out of action consists of a fulcrum arm 111 loosely mounted on the shaft 40 111 and connected with the shaft 113 by the toggle links 118 and 119. The link 118 is pivoted to the arm 117 and to the lower end of the link 119, while link 119 is rigidly secured upon the shaft 113, which is rocked at proper times 45 to straighten or contract the toggle. The arm 117 is so arranged that when the toggle links are straightened the free end of the arm will first engage the top of the bank of sheets and then the further movement of the toggle in straightening will raise the shaft 113 carrying with it the comber supporting arm 110. In this position of the parts the arm 117 acts as a clamp for holding the top sheets in place during the completion 50 of the combing operation by the companion 55 combing wheel. When the combing operation is complete and the feeding off devices are about to act, the rocking sleeve 115 is operated to further raise the shaft 113 which further elevates the combing wheel and lifts the fulcrum arm 111 out 60 of contact with the bank of sheets. The sleeve 115 is rocked for this purpose by means of a cam 120 secured to a cam shaft 121 and arranged to act upon an arm 122 secured to and projecting from the sleeve 115.

65 The shaft 113 is rocked to straighten the toggle 118, 119 (thereby lifting the comb wheel by throwing the fulcrum arm 117 into action) by the action of a spring 123, one end of which is anchored to a stay bolt 124 connecting the side 70 frames 67 and the other end is connected to a lever 125 movably supported upon the shaft 121 and connected through link 126 with the rock arm 127 fixed upon the shaft 113. Through these connections the spring 123 tends to rock the 75 shaft 113 in a direction to straighten the toggle

and lift the combing wheel. The lifting devices are held out of operation with the spring 123 under tension and the operation controlled by an automatic latch consisting of an arm 128 formed integral with the lever 125 and projecting into engagement with a latch nose 129 of a sleeve 130 freely journalled upon a shaft 131 and having a radially projecting arm 132 formed with a vertical opening through which extends a fixed upright rod 133 carrying at its upper end 10 a spring 134 confined against the arm 132 by means of a head or nut 135 adjustably mounted upon the upper end of the upright rod 133.

15 The mechanism for operating the latch just described to automatically arrest the action of the 15 combing wheel, consists of a ratchet disk 136 secured to the shaft 121 in position to be engaged by a pawl on the upper end of the sheet stop 69 which is pivotally mounted at 137 in the lower end of an arm 138 projecting from the sleeve 20 130 of the latch member; with the result that a sheet being combed into registered position moves the pawl of stop 69 into engagement with the ratchet 136 which forces the sleeve 130 rearwardly upon its shaft 131, compressing spring 25 134, and moving the latch nose 129 out of the path of the projecting arm 128, thereby permitting the spring 123 to straighten the toggle and arrest the combing action. After the removal of a registered combed sheet, the resetting cam 30 139 upon shaft 131 passes the anti-friction roller 140 upon arm 128, forcing arm 128 outwardly and permitting the spring 134 to return the latch nose 129 into latched engagement with arm 128 and return the controlling stop 69 to active position to register the succeeding sheet.

The combing mechanism controls, in a manner well understood in this art, (as hereinbefore referred to) the action of the pawl and ratchet mechanism 43, 44 for periodically advancing the 40 fanned out bank of sheets over the supply and feed tables to maintain the sheets in proper position upon the feed table for the action of the 45 combing devices.

Under the plan of operation of the improved 45 reorganized continuous feeding machine the successive sheets are combed forwardly in the same direction in which the bank has been fanned out and partially separated and as each sheet reaches final or registered position its rear end is engaged and raised from the bank by devices which are presented above the tail end of the registered sheet. This feed-off and delivery mechanism will now be described.

50 70 is one of a plurality of tail drags pivotally mounted upon the free ends of levers 71 pivotally supported upon the shaft 64 above referred to. These drags 70 are preferably heavy metal blocks hollowed out and shaped into forwardly presented air blast tubes 72 to which air under 55 pressure may be supplied from any suitable source in the well-known way. The tail drags 70 engage the fanned out bank of sheets above the table 36 just forward of roller 62 and in rear of the tail of the top sheet when it reaches registered 60 position against the trip finger 69, this relative position of the tail drag and sheet combing trips being easily effected by adjusting the feed tables and mechanism carried thereby through the screw 23 and hand-wheel 25 above referred to.

75 73 is one of a series of sheet engaging suckers mounted upon a tubular member 74 extending radially from an air tube 75 connected with a suction pump (not shown) through a flexible tube 76. The air tube 75 supporting the suckers 73 is 75

- pivotedly mounted in the forward ends of parallel arms 71 projecting from a rock shaft 18 freely journalled in the side frame plates 65 and carrying adjacent to one end a mutilated gear 19 with which a reciprocating rack 80 is in constant mesh. This rack 80 is formed upon one part of a two-part pitman 81 guiding at its upper yoke end 82 upon cam shaft 83 which carries a groove cam 84 engaging a stud 85 upon the pitman 81. 10 The two parts of the pitman 81 have a pin and slot lost motion connection 81a and the pitman operates in a guide bracket 85a secured to the face of frame plate 65. The rack 80 or lower pitman part is also formed as a guide yoke straddling rock-shaft 18 and gear 19. While the two-part pitman may be suitably arranged to afford lowering of suckers 73 to varying elevations of the bank of sheets, it will be clear that other suitable well-known means, such as extensible telescopic sucker tubes (not shown) may be employed for providing automatic adjustability of the take-off suckers to the varying elevation of the bank upon the feed table.

Arranged below and parallel with the arms 71 are the links 86 pivoted to side plates 65 and to the tubular members 14 of the suckers for maintaining the suckers in vertical position as they move up from the surface of the bank of sheets to the delivery drop roller mechanism. 25 87 is a delivery feed shaft journalled in the frame plates 65 and carrying delivery feeding rollers 88. 89 are drop rollers journalled upon the rock arms 90 projecting from rock shaft 91 operated by a second rock arm 92 carrying anti-friction roller 93 operating upon a controlling cam 94 keyed to the cam shaft 83 above referred to.

95 are sheet supporting and guiding slots of the conveyor frame which leads from the delivery 40 drop roller mechanism of the feeding machine to the impression cylinder of the printing press.

A driving shaft 96 driven by the printing press operates cam shaft 83 through gears 97, 98, 99 and 100 as indicated in Figures 1 and 2 of the 45 drawings. An inclined telescopic shaft 101, driven by gear 98 and 102, operates the combing mechanisms through gears 103 and 104 in the usual manner.

The feathered or fanned-out bank of sheets is 50 gradually fed forward from the lower supply table 1 through the bank reversing throat and over the drum 26 to the upper feed table 36 where the tapered leading end of the bank is presented in position for the final separating action of the 55 automatically controlled combing mechanisms. As each top sheet actuates the front stops or tripping devices 69, the tail of the top sheet rests in front of and free from the tail drags 10 which engage the next sheet beneath and hold the bank 60 in place. Suckers 73 then engage the tail end of the completely separated top sheet and raise it from the bank and shift it rearwardly (opposite to the separating feeding movement of the bank and combing wheels) into the bight of the drop 65 roller delivery mechanism 88, 89, which quickly removes the sheet from the bank and delivers it upon the conveyor leading to the printing press or other machine. During this feeding-off of sheet, air is shown under the raised tail end of 70 the sheets through the tail drags or other blast devices such as are commonly employed. As each sheet is drawn rearwardly away from the trip fingers 69 beneath the raised combing wheels 68, it will be clear that the combing wheels can be 75 timed to drop upon the bank of sheets and re-

sume their separating action upon the next sheet immediately after the top sheet has completely passed beneath the combing wheels. The combing wheels act upon the bank near the registry edge of the feed table so that a relatively small portion of each sheet has to pass beneath the combing wheels in the reverse or rear feeding-off of the sheets, which relationship provides for the rapid successive separation and delivery of sheets. In this way the speed of operation of the improved machine is greatly increased and meets the requirements for feeding to the modern rapid printing presses. 10

I claim:—

1. The combination with a feed table and means for feeding a fanned-out bank of sheets upon said feed table, of sheet-actuated tripping devices adjacent to the end of said feed table toward which the bank of sheets is fed, sheet-separating combing devices acting above said feed table adjacent to said tripping devices to impart a final separating movement to sheets in the same direction as the bank feed, means under the control of said tripping devices for arresting the action of said combing devices, tail-drags engaging the fanned-out bank of sheets approximately sheet lengths from said tripping devices, feed-off devices arranged to engage and raise the tail end of the top sheet adjacent to said tail-drags, and delivery mechanism arranged to take the raised tail end of the top sheet and move the same rearwardly from the feed table away from said combing and tripping devices. 15 20 25 30

2. The combination with a supply table and a feed table connected by a pile-reversing throat, of means for feeding a fanned-out bank of sheets from said supply table to said feed table, sheet actuated tripping devices upon said feed table remote from said pile-reversing throat, sheet-separating combing devices acting above said feed table adjacent to said tripping devices, means under the control of said tripping devices for arresting the action of said combing devices, tail-drags engaging the fanned-out bank of sheets, and feed-off devices arranged to engage and raise the tail end of the top sheet adjacent to said tail-drags, and move the same rearwardly from the feed table away from said combing devices and tripping devices. 35 40 45

3. The combination with the lower supply table and the upper feed table connected by a pile-reversing throat, of means for feeding a fanned-out bank of sheets from said supply table to said feed table, sheet actuated tripping devices upon said feed table remote from said pile-reversing throat, sheet-separating combing devices acting above said feed table adjacent to said tripping devices, means under the control of said tripping devices for arresting the action of said combing devices, tail-drags engaging the fanned-out bank of sheets approximately the length of sheets from said tripping devices, feed-off devices arranged to engage and raise the tail end of the top sheet adjacent to said tail-drags, and move the same rearwardly from the feed table away from said delivery mechanism arranged to take the raised end of the sheet from said feed-off devices and combing devices and tripping devices. 50 55 60 65

4. The combination with the lower supply table and the upper feed table connected by a pile-reversing throat, of means for feeding a fanned-out bank of sheets from said supply table to said feed table toward the free end of the latter, sheet actuated tripping devices at the free end of said feed table, sheet-separating combing devices act- 70 75 80 85 90

- ing adjacent to the free end of said feed table to comb sheets toward said tripping devices, means under the control of said tripping devices for arresting the action of said combing devices, 5 tail-drags engaging the fanned-out bank of sheets adjacent to the rear end of the top sheet, feed-off devices arranged to engage and raise the rear end of the top sheet, and drop-roller delivery mechanism arranged to take the raised 10 rear end of the top sheet from said feed-off devices and move the same rearwardly from the feed table.
5. The combination with a feed table and means for feeding a fanned-out bank of sheets 15 upon said feed table, sheet actuated tripping devices at the end of said feed table toward which the bank of sheets is fed, sheet-separating combing devices acting upon said bank of sheets adjacent to said tripping devices to augment the 20 sheet-separation in the same direction as the feed of the fanned-out bank, means under the control of said tripping devices for arresting the action of said combing devices, tail-drags engaging the fanned-out bank of sheets in rear of 25 the top sheet, feed-off devices arranged to en-
- gage and raise the tail end of the top sheet adjacent to said tail-drags, means for blowing air beneath the raised tail end of the top sheet, drop-roller delivery mechanism arranged to take the raised rear end of the top sheet and move the same rearwardly from the feed table, and a conveyor arranged to receive sheets from said drop-roller delivery mechanism. 5
6. A sheet feeding machine comprising a feed table arranged to support a bank of sheets, means for feeding and fanning-out a bank of sheets upon and away from the delivery end of said feed table, automatically controlled sheet-combing separating devices acting upon the bank of sheets remote from the delivery end of said table to 10 impart a final separating movement to the sheets in the same direction as the fanning-out by the feeding means, bank holding means engaging the bank in rear of the tail end of the top sheet, and feed-off devices arranged to engage the tail 15 end of the top sheet adjacent to the delivery end of the table and move the same rearwardly away from said combing devices. 20

FRANK L. CROSS. 25
